UNITED STATES PATENT OFFICE.

WILLIAM E. WATT, OF EVANSTON, ILLINOIS.

AIR COOLING AND DEHYDRATING DEVICE.

Application filed July 25, 1924. Serial No. 728,104.

This invention relates to devices for cooling and for partially dehydrating the air contained within enclosures.

One of the objects of the invention is the provision of new and improved means for cooling the air contained in rooms, halls, buildings and the like.

Another object of the invention is the provision of new and improved means for partially dehydrating the air contained in enclosures in which the device is employed.

A further object of the invention is the provision of new and improved means for reducing the temperature in enclosures and more particularly in enclosures occupied by human beings, as dwellings theaters, schools, churches, stores, shops and the like, and simultaneously removing a portion of the moisture contained in said air to thereby render the air in said enclosures more comfortable for human habitation.

Other objects of the invention are the provision of a new and improved device for cooling and partially dehydrating air, that is simple in construction, cheap to manufacture, easily assembled, efficient in operation, and that is not likely to become broken or get out of order.

Other and further objects and advantages of the invention will appear from the following description taken in connection with the accompanying drawings, in which—

Fig. 1 is a perspective view of the device;

Fig. 2 is a longitudinal section thereof; and

Fig. 3 is a section on line 3—3 of Fig. 2.

On the drawing the reference character 10 designates a box or container which may be of any desirable form and composed of any suitable material. In the form of the device selected to illustrate one embodiment of the invention, the container 10 is rectangular in form and composed of sheet metal. The container is provided with an air passage through which air may be caused to move. As shown, the end walls 11 and 12 of the container are provided with openings 13 and 14 respectively for this purpose. The upper wall 15 of the container may form a lid or closure hinged as at 16. The closure 15 is preferably provided with a handle 17 whereby the same may be lifted to permit access to the interior of the container.

It is a well known fact that warm humid air is more uncomfortable than dry air at the same temperature. In other words, hu-

mid air in warm weather will appear to be or feel several degrees warmer than dry air at the same temperature, due to the fact that with dry air the skin is cooled by the more rapid evaporation of perspiration. It is also a matter of common knowledge that the air's capacity for moisture decreases as the temperature decreases. Suitable means are provided for taking advantage of these principles, for not only lowering the temperature but also partially dehydrating or removing a portion of the moisture from the air whereby the same will appear to be at a lower temperature than it actually is. As shown, this is accomplished by employing a condensing surface and maintaining it at a low temperature and so mounting it that the air may circulate about the same and coming in contact with it will become chilled thereby depositing its moisture on the condenser. The moisture thus condensed will be collected in the bottom of the container as at 24. As shown, the condenser is in the form of a receptacle 18 for containing a cooling agent. Any suitable cooling agent may be employed, that shown being a lump of ice 19 which is placed in said receptacle. The receptacle is comparatively shallow and is of less width than the container. Suitable means, as the supporting brackets 21 and 22 are provided for supporting the receptacle in spaced relation to the top, bottom and side walls of the container whereby air directed through the receptacle by any suitable means as the fan 23 will circulate about the receptacle.

The receptacle is supported so that the upper edge of its front wall 25 will extend across the opening 13. The front wall 25 is arranged at an angle to the bottom wall whereby the same will deflect a portion of the air beneath the receptacle. An imperforate baffle 26 is provided which is adapted to extend upwardly and to either side in engagement with the top and side walls of the container to form a deflector in alignment with the rear wall 30 of the receptacle whereby the air entering the opening 13 above the front wall 25 will come in contact with the cooling agent and will be compelled to flow over the sides of the receptacle and mingle with the air entering the lower portion of the opening 13, thus assisting in cooling and causing the same to deposit its moisture on the condensing surfaces of the receptacle.

In order to deflect the air downward on the cooling agent a suitable deflector 27 may be provided. The deflector 27 is preferably hinged as by a detachable hinge 28 whereby the same will automatically adjust itself to the size of the cooling agent. If ice be employed, the rear end of the deflector will rest on the ice and will move downward as the ice melts.

10 The baffle 26 may, if desired be provided with flanges 29 having slots therein for engaging headed pins 31 on the side walls of the container, for positioning the baffle.

15 In the operation of the device a cooling agent as ice is placed within the receptacle and a current of air is caused to flow through the container. The air is directed onto the ice and a portion of its heat is absorbed by the ice, thus melting the ice and forming 20 ice water 33 in the receptacle, which cools the walls of the receptacle to such an extent that the air deflected downward by the front wall 25 and coming in contact with the bottom and side walls of the 25 receptacle will become chilled and deposit its moisture. That portion of the air current flowing on to the ice will flow over the sides of the receptacle and mingling with the adjacent air will assist in cooling the same. The cool air will pass beneath the baffle formed by the rear wall of the receptacle and will flow upward and out into the room or other enclosure through the opening 14 as indicated by the arrows 30 in Fig. 2. The air in the room is not only cooled and partially dehydrated but is caused to be continually circulated by the 35 operation of the fan.

40 While I have shown a fan for forcing air through the container and have shown a receptacle containing ice within the container, it is understood that this disclosure is by way of example only as any suitable means may be employed for causing the air

to flow through said container and any suitable arrangement of condensing surfaces and means for cooling the same may be employed without departing from the spirit of the invention, or scope of the appended claims.

45 50 I claim as my invention:

1. In combination, a casing, a container adapted to contain a cooling agent, supported within said container, means for directing a current of air over and about said 55 container, and a baffle plate at the rear of said container engaging the side walls and top of said casing, said baffle plate terminating short of the bottom wall to form an air passage beneath the same.

2. In combination, a casing having openings in its front and rear walls, a container in said casing spaced from the side walls thereof, adapted to contain a refrigerant, means for supporting said container in spaced relation to the rear wall of said casing and opposite an opening in said front wall, whereby air entering said opening will pass over said container, and an imperforate baffle extending above said container at the 70 rear portion thereof for reflecting the air entering said casing above said container, back over said refrigerant.

3. In combination, a casing having openings in its front and rear walls, a refrigerant container, means for supporting said container in spaced relation to the bottom and rear end walls of said casing, means for directing a portion of the air entering said casing above said container, a baffle 75 extending above said container on the rear portion thereof, and a deflector hinged at the forward portion of said casing and having its rear end adapted to rest on the refrigerant in the container for deflecting air entering said casing about said refrigerant.

70 75 80 85 WILLIAM E. WATT.
